(57) **CLAIM**

The ornamental design for a “tire chain with spikes,” as shown and described.

DESCRIPTION

FIG. 1 is a perspective view of a tire chain with quadrangle spikes embodying my new design;

FIG. 2 is a top plan view of the FIG. 1 embodiment;

FIG. 3 is a bottom plan view thereof;

FIG. 4 is a side elevational view thereof; and,

FIG. 5 is an end view thereof.

The tire chain is shown broken away to indicate indeterminate length.
